Primary Examiner — Keith J Wilson(74) *Attorney, Agent, or Firm* — Tucker Ellis, LLP(57) **CLAIM**

The ornamental design for a canister attachment device, as shown and described.

DESCRIPTION

FIG. 1 is a top perspective view of a canister attachment device showing our new design;

FIG. 2 is a bottom perspective of the canister attachment device illustrated in FIG. 1;

FIG. 3 is a left side view of the canister attachment device illustrated in FIG. 1;

FIG. 4 is a front view of the canister attachment device illustrated in FIG. 1;

FIG. 5 is a right side view of the canister attachment device illustrated in FIG. 1;

FIG. 6 is a rear view of the canister attachment device illustrated in FIG. 1;

FIG. 7 is a top view of the canister attachment device illustrated in FIG. 1; and,

FIG. 8 is a bottom view of the canister attachment device illustrated in FIG. 1.

The broken lines in the drawings illustrate the portions of the canister attachment device that form no part of the claimed design.

1 Claim, 4 Drawing Sheets(56)
